MECHANISM FOR COUNTING AND STACKING ARTICLES

Kenneth H. Hansen, Elm Grove, Frederic E. Howdle, Milwaukee, and Theodore B. Jochem, Wauwatosa, Wis., assignors to Cutler-Hammer, Inc., Milwaukee, Wis., a corporation of Delaware

Filed Jan. 16, 1956, Ser. No. 559,480

10 Claims. (Cl. 209—82)

This invention relates to improvements in mechanism for counting and stacking magazines and the like, particularly to a duplex unit having two stackers operated from a common drive while retaining independent counting, collecting and bundle delivery, and to associated devices for detecting and rejecting non-standard size magazine, and detecting jams at such stackers and diverting the incoming magazines while the jam is cleared.

Since the duplex unit has a common drive, both stackers must be shut down when a jam occurs in one. This means that both feeder lines must be stopped or their delivery to the stackers temporarily diverted to an emergency receiver.

One object of this invention, therefore, is to detect and remove from the delivery stream an irregular magazine or like article.

Another object of this invention is to detect a jam at a stacker and automatically divert the streams of magazines or the like on the feeder lines from the stackers while a jam is being cleared therein.

A stacker of the type referred to and its controls is described and claimed in Patent No. 2,769,378, issued November 6, 1956. Two of such stackers are mounted side by side to utilize common shafts and drives. The counting systems and collecting baskets with their operating cams for each stacker are independently operated for each stream of magazines. The stackers may be stopped without losing the count which may be restarted without a warm-up period. To decrease the possibility of a jam occurring at the stackers, two photo-electric relays and light beam sources (sometimes referred to as beam assemblies and photo-relays) are placed in each stream and spaced so that an oversize magazine will cut both beams for a simultaneous period. This signal energizes a relay system to momentarily swing a diverting vane into the stream and remove such magazine. A detector switch located at the mouth of each stacker signals a jam (overlapping of magazines) and energizes the relay system to swing both diverting vanes into the streams and continually remove the magazines from such streams. Such diversion will continue until the jam is cleared and the system reset. The relay system is coordinated with the photo-relays to prevent swinging of the diverting vanes when a magazine is in the path of swing of such vanes. Reject transfer conveyors may temporarily carry away the magazines during the clearing of a jam.

The invention may be understood in detail from the following description of a specific embodiment when read in connection with the accompanying drawings, in which:

Fig. 1 is a schematic top plan view of a device embodying the present invention incorporated in each stream of articles extending from each collator to each stacker;

Fig. 2 is a schematic view in side elevation of such device; and

Fig. 3 is a schematic diagram of the electrical controls forming a part thereof.

The jam detecting and jam preventing devices shown

2

in the drawings are incorporated in a duplex unit in which magazines in a first stream move from a collator 10 to a stacker 22 and in an adjacent second stream from a collator 11 to a stacker 23. The parts in the first or lower stream are identified by even numbers and like parts in the second or upper stream are identified by the next higher odd number. Transfer conveyors 12 and 13 move the magazines 33 from the collators. From these transfer conveyors the magazines are picked up by canvas belt conveyors 14 and 15 transversely arranged with respect to such transfer conveyors and on which the magazines 33 are conveyed to the stackers 22 and 23. There is incorporated between the conveyors 14 and 15 and such stackers reject stations at which single magazines can be rejected or an entire stream diverted for the time necessary to clear a jam.

These reject stations consist of horizontal wire belt conveyors 16 and 17 leading to inclined belt wire conveyors 18 and 19 which include a base and holding cover of well-known design. The inclined conveyors carry magazines to horizontal wire belt conveyors 20 and 21 for delivery to the throat of the stackers 22 and 23. Bundles formed in such stackers are delivered on delivery conveyors 24 and 25. Individual rejected magazines or a continuous diverted stream thereof are moved laterally away from the reject stations on transverse conveyors 26 and 27. Both the stackers 22 and 23 and the conveyors 18, 19, 20 and 21 leading to them are driven by a common motor 28. A separate motor 29 operates independently 30 to provide a drive common to the conveyors 14, 15, 16, 17, 26 and 27. Motors 30 and 31 provide the drive for the collators 10 and 11 and the transfer conveyors 12 and 13.

The speed of all conveyors is constant and related so 35 that the magazines 33 when traveling to the stackers on conveyors 14 and 16 are spaced a distance somewhat greater than the length of the magazine. Magazines larger than a specified length should be ejected as not acceptable. To accomplish this (and also continuous diversion) there is positioned in the reject stations spaced photo-relay and light cell assemblies which provide in each stream two beams passing vertically through the spaced belts of the conveyors 16 and 17 so as to be broken by the magazines 33 moving on such conveyors. The beam 40 first broken in conveyor 16 is designated E and that in conveyor 17 is designated EE. The beam second broken in conveyor 16 is designated F and that in conveyor 17 is designated FF. These first and second beams are spaced so that a magazine longer than a specified dimension will interrupt both beams at one time. The relay control mechanism hereinafter described in detail will cause pivoted vanes 34 and 35 to be swung from the inclined position shown in the full lines whereby they direct the stream of magazines onto the inclined conveyors 18 and 19 to the horizontal position shown in the broken lines to no longer intercept magazines on the conveyors 16 and 17 and permit them to fall on conveyors 26 and 27 for removal from the streams. Electromagnetic means such as the solenoids 36 and 37 are energized to move 45 the vanes from non-diverting to diverting position. Depending upon the signal received the vanes will operate individually to remove a single oversize magazine from either stream or will operate conjointly to divert both streams from the stackers. In order to automatically 50 detect a jam occurring at the mouth of the stackers 22 and 23 there is positioned above the conveyors 20 and 21 jam detector rollers 38 and 39. These rollers operate jam detector switches 40 and 41 when magazines enter the stackers overlapped.

The grooved pulleys and wire belts forming the various wire belt conveyors, the vanes 34 and 35 and the method of installing them between the horizontal conveyors 16

and 17 and the inclined conveyers 18 and 19 and the mechanism to swing them from non-diverting to diverting position under the control of the solenoids 36 and 37 are well known to those skilled in this art. For the purposes of this invention it is merely required to know that when a solenoid is energized its associated vane is swung to the horizontal diverting position shown in the broken line of Fig. 2 and that when a solenoid is de-energized such vane is returned to the inclined non-diverting position.

In the side-by-side duplex unit described economies are obtained by driving both stackers by the common drive motor 28 and by utilizing single shafts and a common supporting frame for all of the pulleys and drums that are in axial alinement. However, this entails some complications of control which will be described. Because there is a common drive for both stackers their operation must be coordinated so that when it is necessary to stop one to eliminate a jam, the other is also stopped. However, in stopping a stacker it is desirable to keep the counting section energized so that the count is not lost and a heat-up period not again required. It is also economical in the operation of the entire system to keep the collators 10 and 11 and the conveyers 12, 13, 14, 15, 16, 17, 26 and 27 in operation during the correction of a jam.

The operation of the vanes and the automatic control of the various motors to accomplish the rejection of oversize magazines and to divert each stream during a jam removal period is controlled by an electrical control system. This system includes the control system used in operating the stackers and described in the aforementioned Patent No. 2,769,378 but only such parts of said stacker control system which cooperate with parts of this system will be described in detail and reference can be had to such application for greater detail. Where possible the same letters and numbers will be used for like elements of the system described and the system of such application. The counting and bundle forming operation of the stackers is essentially controlled by photo-relays P and PP (Fig. 3) and their associated light sources Lt. These stacker relays, the light beam assemblies E, F, EE and FF, the jam detection switches 40 and 41, the vane solenoids 36 and 37, the circuit control relays, and the various manually operated switches are all shown in the circuit schematically and diagrammatically illustrated in Fig. 3. Each relay has its solenoid and the contacts controlled thereby are designated by the same capital letter. Each normally open contact is further designated by an odd number and each normally closed contact by an even number. The relays and contacts controlled thereby are vertically alined, and the contacts are shown in the positions assumed before the start button 144 is closed and a warm-up period transpired. The photo-relays are shown in the position assumed when the light beam is broken. After the warm-up period and when the light beam is not broken these relays will be in the upper position and opposite to that shown in Fig. 3. The normally open contacts are indicated by contact bars spaced below the contacts. The normally closed contacts are indicated by contact bars placed on top of the contacts. All of the relays shown are the standard non-latching type. The control mechanism and circuits for the stackers not shown in detail are symbolically illustrated by the boxes identified as BC1 and BC2.

The arrangement of the control circuit can best be understood from a description of the operation of the relays included therein during the sequences following normal starting and subsequent sensing of oversize magazines and jams. When starting switch 144 is closed, with jam switches 154 closed, relay A is energized and maintained energized by its own interlock contacts A1. This applies voltage on lines L1 and L2 through the contacts B2 and BB2, to an alarm 42 and to the transformer for the photo-relays P and PP and their lights Lt. The con-

trol sections and bridge rectifiers for the clutches for the stackers also have such voltage applied to them by the relay A by a circuit not shown. When the photo-relays heat up the light beam will cause the relays P and PP to be energized and the contacts P1 and PP1 to close. This energizes the relays B, C, D, BB, CC and DD. The energizing of B and BB breaks the circuit to the alarm 42 through the contacts B2 and BB2 and closes the contacts B1 and BB1 to energize the motor relay M. 10 Relay M closes contacts M1, M3, M5 to place motor 28 on the lines L1, L2, and L3 starting the stacker units. Relay M closes contacts M7 to start the motors 30 and 31 for the collators and closes contacts M9 to start the reject motor 29. The contacts B4 and BB4 maintain the relays B and BB energized through their own interlock. Thus the motor 29 will remain energized even when the light beam for the photo-relays P and PP is broken during the counting action. The relays C and D are independently operated by the breaking of the beam of the photo-relay P each time a magazine passes through such beam. The same is true of the relays CC and DD upon the interrupting of the beam of photo-relay PP. The contacts C1 and D1 energize the counters and stacking controls in the box BC1 and the contacts CC1 and DD1 energize the counters and stacking controls in the box BC2. Thus the two stackers independently count magazines passing therethrough. At the end of a counting and stacking operation the clear switch 152 is opened to reset the batch counters and eject any incomplete bundles. The stackers are stopped by opening the manual switch 150.

When there is a jam in one of the stackers, jam switch 154 is manually opened to break the circuit to the lights Lt in both stackers and deenergize the relay M stopping the motor 28 for both stackers. The jam may be cleared without affecting the count then registered as the light beam is de-energized. However, the photo-relays, counter and the other control systems are not deenergized so that when the jam has been cleared and the jam switch 154 closed, the counting and stacking operations will continue without loss of the count or without a warm-up period. It should be noted that the opening of the jam switch 154 will also open the contacts M7 and M9. This would stop the collator motors 30 and 31 and the reject motor 29. However, these motors will continue to run if, before the jam switch 154 is opened, either of the automatic jam detector switches 40 and 41 has been closed. The closing of these jam detector switches energizes relay H closing the contacts H1 and H3 to maintain the circuits to the motors 29, 30 and 31.

Assume that while the device is in operation with streams of magazines being carried by the conveyers into the stackers, an oversize magazine enters the reject station on the conveyer 16. As the leading edge of such magazine cuts the beam at photo-relay E, the contact E2 will close and the circuit will be established through the relay G up to the contacts F2. While the beam at photo-relay E is still broken, the leading edge of the oversize magazine will break the beam of photo-relay F. Contacts F2 will close completing the circuit through relay G. The energizing of relay G closes contacts G1 and G3. The contacts G3 energize the solenoid 36 to shift the vane 34 to the horizontal position. This can occur without interference from preceding magazine which has already started up the inclined conveyer 18. The contacts G1 lock the relay G in circuit with the contacts F2 as they close and the relay G will remain energized until the oversize magazine leaves the beam of photo-relay F permitting such relay to be energized to open contacts F2. This permits the oversize magazine to drop onto the discard conveyer 26 and provides enough time for the solenoid 36 to hold the vane in the horizontal position until the oversize magazine is sufficiently out of the way to permit the vane to move back to the inclined position. The distances between the vanes 34 and 35 and the photo-

relays E, F, EE and FF are initially adjusted in proportion to the speed of the conveyer and the speed of operation of the solenoids 36 and 37 to provide for the proper timing and correct operation. The sequence of operations is the same when an oversize magazine enters the reject station on the conveyer 17 to cut simultaneously the beams of photo-relays EE and FF. In such stream the relay GG is energized closing the circuit through the solenoid 37 by the contacts GG3 to control the operation of vane 35. Relay GG by the closing of contacts GG1 will remain energized until the following edge of the oversize magazine leaves the beam of the relay FF opening the contacts FF2. Since the reject of oversize magazines does not in any way affect the operation of the motor 28 for the stackers or the motors 30 and 31 for the collators and the motor 29 for the conveyers, there is no need for interrelating the control systems for each stream up to this point. Each of the reject stations in the separate streams operates independently of the other.

While the disposal of such oversize magazines effectively lessens the number of jams which will occur at the stackers, it is possible that such jams can occur. When an overlapping of magazines (jam) occurs on the conveyer 20 at the mouth of the stacker 22, the roller 38 will be raised to close jam detector switch 40. Circuits will then extend from contacts E2 and EE2 to relays H and HH. However, these relays will not be across the line until the beams of photo-relays E and EE are interrupted closing contacts E2 and EE2. When magazines break the beams of photo-relays E and EE, contacts E2 and EE2 close energizing relays H and HH. The circuits now extend to relays G and GG. Relays H and HH through their contacts H1 and HH1 extend the circuits through relays J and JJ, contacts H3 and HH5 and contacts K2 and KK2 to the contacts F2 and FF2. When the beams of photo-relays F and FF are cut, the contacts F2 and FF2 close and relays G, GG, J and JJ are energized. The contacts G3 and GG3 energize the solenoids 36 and 37 and the contacts G1 and GG1 maintain the circuits around contacts E2 and EE2. Contacts G1, J1 and K2 maintain relay J around the contacts E2, H1, H3 and HH3. Contacts GG1, JJ1 and KK2 maintain relay JJ around the contacts EE2, HH1, HH5 and H5. Contacts J3 and K2 maintain relays G and J around contacts F2 and contacts JJ3 and KK2 maintain relays GG and JJ around contacts FF2. Thus the vanes 34 and 35 will remain in the horizontal position after the beams of photo-relays E, EE, F and FF are reestablished. Magazines on both streams will continue to be diverted from the conveyers 16 and 17 to the reject conveyers 26 and 27. The operation of the vanes 34 and 35 is not simultaneous. Each operates independently in correlation with passage of magazines through their respective light beams. However, once a jam has been sensed by either of the jam switches 40 or 41 each vane will move to diverting position as soon as a magazine has cut both spaced beams in the reject station associated with such vane. If no magazines were moving along in the stream other than the one on which the jam occurred the vane in that stream would not move to diverting position. Contacts J5 or JJ5 energize the relay N and close contacts N1 and N3 to maintain the circuits to the motors 29, 30 and 31, when contacts M7 and M9 are opened as the result of opening jam switch 154 to clear the jam in the stacker 22. A like sequence takes place if the jam detector switch 41 were closed by the result of a jam on the conveyer 21. This assures that there will be a diversion of both streams of magazines from the reject station. This is necessary because both stackers must be shut down even to eliminate the jam in one stacker.

As previously explained, the opening of jam switch 154 stops the stacker motor 28 but does not stop the functioning of the relays and counter units so that the partial count is maintained and will be picked up again upon the closing of the jam switch 154. The light sources Lt are deenergized to prevent a false count occurring

during the removal of the jam. After both vanes 34 and 35 have been shifted to the reject position and the relays G, GG, J and JJ energized and locked across the line, the jam detector switches 40 and 41 can be reset and the jam cleared in the manner described.

After the jam has been cleared the jam switch 154 is closed energizing the relay M and starting the stacker motor 28 and energizing the lights Lt. The system is then returned to stacking conditions by closing both contacts of reset switch 43. Relay M closes contacts M13 placing relays K and KK in the circuit so that upon the closing of reset contacts 43, both relays K and KK will be placed across the line and energized. The energization of relay K opens contact K2 deenergizing relay J. The energization of relay KK opens contacts KK2 deenergizing relay JJ. If there is no magazine breaking the beam of relay F, contacts F1 will be closed and relay K will remain energized through closed contacts K3. If there is no magazine in the beam of relay FF, contacts FF1 will be closed and relay KK will remain energized through contacts KK3. Closed contacts K1 maintain the circuit through relay G and closed contacts KK1 maintain the circuit through relay GG thus still holding the vanes in horizontal position. When a magazine enters the beam of relay F or relay FF, the contacts F1 and FF1 will open deenergizing the relays K and KK. At the same time the contacts F2 and FF2 will close thus still maintaining the relays G and GG in energized position. However, when the magazine leaves the beams of relays F and FF, contacts F2 and FF2 will open thus breaking the circuit to the relays G and GG. This deenergizes the solenoids 36 and 37 and the vanes 34 and 35 will move to the inclined position without any interference from a magazine on the conveyers 16 and 17. The magazines will thereafter be deflected upwardly to the inclined conveyers 18 and 19 and the stacking continued. The deenergizing of relays G and GG also breaks the circuits to relays J and JJ. The circuits are now in normal position for continuing the counting and stacking while detecting and rejecting oversize magazines in either of the lines feeding the stackers independently of each other and sensing jams and automatically diverting both streams in such case.

Although one embodiment of the invention is shown and described herein, it will be understood that this application is intended to cover such changes or modifications as come within the spirit of the invention or the scope of the following claims.

We claim:

1. For use with a counting and stacking mechanism to detect and reject off-sized articles from a stream of articles feeding such mechanism and to detect a jam at such mechanism and divert the stream of articles feeding such mechanism while such jam is cleared, in combination, two pairs of light sources and aligned photo-relays, said pairs being spaced apart a predetermined distance along the path of travel of the articles to the mechanism for interruption of light beams falling on the photo-relays by passage of the articles, a member movable to one position wherein it directs articles into the mechanism and operable to another position wherein it diverts articles away from the mechanism, electroresponsive means energizable to move said member from said one to said other position, control means comprising means responsive to concurrent deenergization of both of said photo-relays to energize said electroresponsive means, means responsive to a jam occurring at the mechanism and deenergization of one of said photo-relays to energize said electroresponsive means continuously, and reset means including switch means manually operable to initiate deenergization of said electroresponsive means and means responsive to said operation of said switch means and reenergization of the photo-relay last to be deenergized to complete the deenergization of said electroresponsive means.
2. The combination according to claim 1 wherein said electroresponsive means is a solenoid operator, said means responsive to deenergization of both of said photo-

relays is an electromagnetic relay energizable by such response to complete energizing connections to said solenoid operator, and wherein the last recited means comprises a switch operable to close upon occurrence of a jam, a second electromagnetic relay energizable by the aforementioned closure of said switch and deenergization of one of said photo-relays and means including a third electromagnetic relay for which energizing connections are completed by energization of said second electromagnetic relay and which when energized maintains energizing connections for itself and the first mentioned electromagnetic relay regardless of reopening of either switch or reenergization of said other of said photo-relays.

3. The combination according to claim 2 wherein said reset means comprises a second switch and a fourth electromagnetic relay energizable by closure of said second switch to interrupt the energizing connections for said third relay while maintaining said first mentioned relay energized pending reenergization of the other said photo-relays.

4. For use with a pair of article stacking mechanisms and a pair of supply conveyors individualized thereto, in combination, a first light source and aligned photo-relay disposed across the path of travel of each conveyor, a second light source and aligned photo-relay disposed across the path of travel of each conveyor in spaced apart relation a predetermined distance along the direction of travel of articles, members interposed between each conveyor and its associated stacking mechanism and each being movable between one position affording transfer of articles to the latter and another position affording directing of articles away from the same, electroresponsive means for each of said members energizable to move its associated member to said other position, control means for each of said electroresponsive means including means responsive to simultaneous deenergization of both photo-relays associated with a conveyor to energize its associated electroresponsive means, and control means including switches responsive to jams occurring at either stacking mechanism to initiate and maintain energization of both of said electroresponsive means, which energization, in each case, is completable following deenergization of the first photo-relay associated therewith.

5. The combination according to claim 4 wherein the last mentioned control means further includes means for manually initiating deenergization of both of said electroresponsive means, for individual completion of deenergization by following reenergization of the second photo-relay respectively associated therewith.

6. The combination according to claim 4 wherein said electroresponsive means are electromagnetic solenoid operators, said means responsive to deenergization of both photo-relays associated with a conveyor are first and second electromagnetic relays for which energizing connections are completed by such response, and wherein the last recited control means includes third and fourth electromagnetic relays for which energizing connections are respectively completed by closure of either of said jam switches and deenergization of an associated second one of said photo-relays, and means including fifth and sixth electromagnetic relays for which energizing con-

nections are completed by energization of said third and fourth relays, respectively, and which when energized maintain energizing connections for themselves and said first and second relays, respectively, regardless of reopening of either of said jam switches or reenergization of said photo-relays.

7. The combination according to claim 6 together with control reset means comprising a third switch and seventh and eighth electromagnetic relays energizable by closure of said third switch to interrupt the energizing connections for said fifth and sixth relays, respectively, while maintaining the energizing connections to said first and second relays, respectively, pending reenergization of the second photo-relays associated with each conveyor in each case.

8. In combination, a pair of article stacking mechanisms, an electric motor for commonly driving both of said stacking mechanisms, supply conveyors associated with each of said stacking mechanisms, a second motor for commonly driving both of said supply conveyors, movable members interposed between each stacking mechanism and its supply conveyor, solenoid operators for each of said members energizable to move its associated member from a position directing flow of articles to an associated stacking mechanism to another position diverting flow of articles from the latter, and control means comprising means for completing energizing connections to both of said motors, a first light source and aligned photo-relay disposed across the path of each of said conveyors, a second light source and aligned photo-relay disposed across the path of each conveyor a predetermined distance apart from said first light and photo-relay in the direction of travel of the articles, like means which are each responsive to simultaneous deenergization of both photo-relays of an associated conveyor to energize the associated solenoid operator, and means including switches responsive to jams occurring at either of said stacking mechanisms to initiate and maintain energization of both of said solenoid operators, the last mentioned energization in both cases being completable as a result of following deenergization of the first photo-relay associated therewith.

9. The combination according to claim 8 wherein said control means further includes means responsive to the aforementioned action of said switches to insure maintenance of energization of said second motor in the event energization of the first mentioned motor is interrupted.

10. The combination according to claim 9 wherein said control means further includes reset means for initiating deenergization of both solenoid operators, which deenergization, in each case, is completable by reenergization of the second photo-relay associated therewith.
